(57) **CLAIM**

The ornamental design for a lid support, as shown and described.

DESCRIPTION

FIG. 1 is a top, front perspective view thereof, the broken lines showing environment which forms no part of the design;

FIG. 2 is a front elevational view of a lid support showing my design therefor;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

Throughout the drawings, broken lines show environment and form no part of the design.

1 Claim, 5 Drawing Sheets(56)
